UNITED STATES PATENT OFFICE.

GEORGE HENRY WHEARY, OF RACINE, WISCONSIN.

CORNER CONSTRUCTION FOR TRUNKS, BOXES, AND THE LIKE.

1,235,948.

Specification of Letters Patent. Patented Aug. 7, 1917.

Application filed June 12, 1915. Serial No. 33,697.

To all whom it may concern:

Be it known that I, GEORGE HENRY WHEARY, a citizen of the United States, and resident of Racine, in the county of Racine 5 and State of Wisconsin, have invented new and useful Improvements in Corner Constructions for Trunks, Boxes, and the like, of which the following is a description, reference being had to the accompanying drawings, which are a part of this specification.

My invention has relation to improvements in edge constructions for trunks, boxes, and the like.

Heretofore in the construction of trunks, particularly of the cheaper grade, the body of the trunk has been made up of pieces of lumber nailed together on all edges, and covered on the outside with canvas, or other material. Almost the entire strength of this 15 type of trunk has resided in the joining points of the lumber, and these joining points or edges were fastened together by nails. It will be readily understood that these nails themselves formed the only resistance to the 20 hard bumps and knocks to which the trunk will be subjected. It was, of course, necessary in this style of trunk to provide thick lumber, in order to secure the necessary strength to permit of the nailing of the sides 25 or panels together. The nails in this old style of trunk are generally arranged in a single line, joining the edges of the trunk together and these nails were driven into the lumber. It follows that a trunk of the 30 character described is open to the objection that if it is thrown down so that the edge strikes the ground, the shock will be concentrated at the edge, and it naturally follows that the edge will become loosened 35 and the strength of the trunk decidedly impaired.

The construction of trunk above mentioned was followed by a trunk styled a "reinforced" trunk, employing separate 40 wooden edge pieces, the exterior surfaces of said edge pieces oftentimes being of rounded contour so as to present round edges for all of the edges of the trunk. These edge pieces have been provided with shoulders 45 against which the edges of the sides or pan-

els of the trunk abut; in other words, the edges of the sides have a dove-tailed connection with the edge pieces, and all the nails from the sides of the trunk enter the reinforced edge obliquely, not perpendicularly. 55

While the round edge construction last referred to has proven a great improvement over the previously referred to square edge construction, yet even this last referred to construction is open to some objections and 60 disadvantages, among which may be mentioned the fact that in said construction it is necessary to cover the numerous edges or joints with a covering of fiber, metal, or other material, in order to give the edges a 65 finished appearance.

It is one of the primary objects of the present invention to provide a construction wherein the use of lumber at the edge pieces is rendered entirely unnecessary, so that, if 70 desired, not only can the edge pieces be made of metal, but the side pieces or panels of the trunk or box can also be made of metal, or material having like qualities, or fiber, if preferred, thereby enabling very 75 thin material to be used in the make-up of the trunk or box, in view of the fact that it is not necessary in the improved construction to drive nails edgewise into the material. 80

Another important object of the invention is the provision of resilient edge pieces, the resiliency permitting the trunk to resist shocks, when thrown heavily to the ground, and which so frequently occurs during trans- 85 portation of trunks or boxes.

With the above, and other incidental objects in view, the invention consists of the devices and parts, or the equivalents thereof, as hereinafter more fully set forth. 90

In the accompanying drawing,

Figure 1 is a perspective view of one corner of a trunk or box equipped with my improvements, showing the corner fixture secured in place;

Fig. 2 is a similar view showing the said corner fixture removed;

Fig. 3 is a section on the line 3—3 of Fig. 2;

Fig. 4 is a cross-section taken on the same 100

plane as Fig. 3, but showing a modified form of construction; and

Fig. 5 is a cross-section on the same plane, showing a still further modification.

5 Referring to the drawing, the numeral 6 indicates the upright side pieces or panel of a trunk or box, and 7 a horizontal piece thereof. The edges of the side pieces and horizontal piece are separated from each 10 other, as clearly shown in the drawing, and are united by means of the improved edge pieces herein shown and described.

15 The improved edge piece is advisably formed of metal, preferably sheet steel, as this material will best serve to secure the resiliency, spring, or yielding quality which is desired. However, I do not wish to be understood as limiting myself specifically to sheet steel, or other metal but wish to be understood as considering other materials 20 which are capable of being bent and formed as shown in the drawing, as within the spirit and scope of my invention.

25 In the Figs. 1 to 3 form of construction, each elongated edge piece is shown as constructed from a single piece of material bent to form an intermediate member 8 of rounded form, or convex on its outer surface. Two legs 9—9, each leg formed by 30 doubling the material upon itself, and terminal securing flanges 10—10 are provided. The edge piece is so arranged that the respective legs 9 abut against opposed edges of the sides or panels of a trunk or box, and the respective end securing flanges 10 lie 35 against and are secured to the outer surfaces of the sides or panels. Any desirable means for securing the flanges may be adopted, but I prefer to employ rivets 11 driven through said flanges and through 40 the sides or panels of the trunk or box, the heads of the rivets bearing against the outer faces of the sides or panels, and the ends of the rivets being upset against washers 12.

45 Where the ends of two of the horizontal edge pieces are adjacent to the end of the vertical edge piece, the flanges 10 overlap, as clearly shown in Fig. 2, and the space or opening which would otherwise be left 50 between adjacent ends of said edge pieces is bridged by a corner fixture 13, as clearly shown in Fig. 1.

55 It will be seen from the foregoing description of the construction shown in Figs. 1 to 3 that opposed edges of the sides or panels of the trunk or box are not in contact with each other, but are held spaced apart by the intermediate member 8, the said opposed edges occupying diagonal 60 planes with respect to each other. It, therefore, follows that a trunk or box having edges of the character described, and especially when composed of spring metal, when getting the hard knocks to which they

are invariably subject, will resist the shock 65 owing to the resilience or spring of the material forming the edge piece; and in the Figs. 1 to 3 form of construction wherein the member 8 is of rounded formation, no sharp corners are presented, whereby liability of injury to the trunk is greatly reduced.

70 A further advantage of my construction is that the use of nails can be entirely dispensed with, merely rivets passing through the securing flanges and through the sides or flanges being required.

75 Furthermore where wooden edge pieces are employed, as heretofore, it has been necessary for appearance sake, to cover not only the sides or panels, but also the wooden edge pieces with canvas, fiber, metal or other material, in order to give the edges a finished appearance. In the present invention, the use of wooden edge pieces is rendered 80 unnecessary, so that, if desired, not only can the edge pieces be made of metal, or material having like qualities, thus making the structure fireproof, but furthermore very thin material such as metal, fiber or thin wood 85 can be employed, inasmuch as nails are not necessary, and also an outer covering of canvas, fiber, metal and the like is not essential as the paneling and edge pieces may be 90 of uniform and ornate material.

95 The modification illustrated in Fig. 4 of the drawing is similar to the Figs. 1 to 3 form excepting that the intermediate member, which is designated in Fig. 4 by the numeral 8' is of angular form on its outer 100 surface, instead of rounded form.

Fig. 5 illustrates a modification wherein the legs, designated in Fig. 5 by the numeral 9' are continued around and against the inner sides of the side pieces or panels, and the rivets 11 extend through the portions which are against said inner sides of the panels.

105 What I claim as my invention is:

1. An edge construction for trunks, boxes and the like, consisting of a strip of material having an outer medial portion, inwardly extending leg portions constructed by doubling the material upon itself, and outer terminal securing portions.

110 2. An edge construction for trunks, boxes and the like, consisting of a strip of spring material having an outer medial spring portion, inwardly extending leg portions constructed by doubling the material upon itself, and outer 115 terminal securing portions.

120 3. An edge construction for trunks, boxes and the like, constructed from a strip of flat spring metal, bent to form a medial outwardly curved spring portion, inwardly extending leg portions constructed by doubling the material upon itself, and outer 125 terminal securing portions.

4. An edge construction for trunks, boxes and the like, constructed from a single piece of flat spring metal, bent to form a medial outwardly curved spring portion, inwardly extending leg portions constructed by doubling the material upon itself, said leg portions provided with extensions extending at angles therefrom, and terminals securing members.
5. The combination with a trunk, box and the like, comprising sides or panels spaced apart edgewise, of devices disposed along the non-contacting corner edges of the sides or panels, each device consisting of an outer medial portion bridging the space between the non-contacting edges of the sides or panels, inwardly extending leg portions, said leg portions bearing against the edges of the sides or panels, and outer terminal securing portions secured to the outer surfaces of the sides or panels.
6. The combination with a trunk, box or the like, comprising sides or panels spaced apart edgewise, of devices disposed along the non-contacting corner edges of the sides or panels, each device composed of spring metal having an outer medial spring portion bridging the space between the non-contacting edges of the sides or panels, inwardly extending leg portions constructed by doubling the material upon itself, said leg portions bearing against the edges of the sides or panels, and outer terminal securing portions bearing against and secured to the outer surfaces of the sides or panels.
7. The combination with a trunk, box or the like, comprising side pieces or panels spaced apart edgewise, of devices disposed along the non-contacting corner edges of the sides or panels, each device constructed from a single piece of flat spring metal, bent to form an outer medial spring portion bridging the space between the non-contacting edges of the sides or panels, inwardly extending leg portions constructed by doubling the metal upon itself, said leg portions bearing against the edges of the sides or panels, and outer terminal securing portions bearing against and secured to the outer surfaces of the sides or panels.
8. The combination with a trunk, box or the like, comprising side pieces or panels spaced apart edgewise, of devices disposed along the non-contacting corner edges of the sides or panels, each device consisting of a single piece of flat spring portion, bent to form an outer medial outwardly curved spring portion bridging the space between the non-contacting edges of the sides or panels, outwardly extending leg portions constructed by doubling the material upon itself, said leg portions bearing against the edges of the sides or panels, and outer terminal securing portions bearing against and secured to the outer surfaces of the sides or panels.
9. The combination with a trunk, box or the like, comprising side pieces or panels spaced apart edgewise, of devices disposed along the non-contacting corner edges of the sides or panels, each device composed of a medial portion bridging the space between the non-contacting edges of the sides or panels, inwardly extending leg portions constructed by doubling the material upon itself, said leg portions bearing against the edges of the sides or panels, and said doubled material extending at angles from the leg portions, the extensions bearing against the inner surfaces of the sides or panels, and outer terminal securing portions opposite the extensions, and bearing against and secured to the outer surfaces of the sides or panels.
10. The combination with a trunk, box or the like, comprising sides or panels spaced apart edgewise, a device disposed along the non-contacting corner edges of the sides or panels, each device consisting of an outer medial portion bridging the space between the non-contacting edges of the sides or panels, inwardly extending leg portions constructed by doubling the material upon itself, said leg portions bearing against the edges of the sides or panels, and outer terminal securing portions bearing against and secured to the outer surfaces of the sides or panels, and a corner fixture secured in place and covering the opening which would otherwise be left at the point where the ends of a plurality of the devices are adjacent to each other.
11. The combination with a trunk, box or the like, comprising sides or panels spaced apart edgewise, a device disposed along the non-contacting corner edges of the sides or panels, each device consisting of an outer medial portion bridging the space between the non-contacting edges of the sides or panels, inwardly extending leg portions constructed by doubling the material upon itself, said leg portions bearing against the edges of the sides or panels, and outer terminal securing portions bearing against and secured to the outer surfaces of the sides or panels, the said securing portions of the several devices having overlapping engagement one with the other at the point of meeting of said terminal portions, and a corner fixture secured in place and covering the opening which would otherwise be left at the point where the ends of a plurality of the devices are adjacent to each other.
12. The combination with a trunk, box or the like, comprising sides or panels spaced apart edgewise, of devices disposed along the non-contacting corner edges of the sides or panels, each device consisting of an outer

medial portion bridging the space between the non-contacting edges of the sides or panels, leg portions constructed by doubling the material upon itself, said leg portions being on inclined planes converging inwardly, the said inclined leg portions bearing against the inclined edges of the sides or panels, and terminal securing portions dis-

posed against and secured to the outer surfaces of the sides or panels.

In testimony whereof, I affix my signature, in presence of two witnesses.
